UNITED STATES PATENT OFFICE.

WEBB JAY, OF CHICAGO, ILLINOIS.

VACUUM FEED DEVICE FOR ELEVATING LIQUID.

1,268,780.

Specification of Letters Patent.

Patented June 4, 1918.

Application filed October 26, 1914. Serial No. 368,580.

To all whom it may concern:

Be it known that I, WEBB JAY, a citizen of the United States, residing at Chicago, in the county of Cook and State of Illinois, have invented new and useful Improvements in Vacuum Feed Devices for Elevating Liquid, of which the following is a specification, reference being had to the accompanying drawings, forming a part thereof.

10 The purpose of this invention is to provide an improved device adapted for elevating liquid by means of a partial vacuum or suction, particularly designed and adapted for elevating the liquid fuel supply for internal combustion engines, from a lower main supply tank to an upper receptacle from which it may be supplied by gravity to the carburetor, or for elevating a lubricating liquid from a main supply tank at a low 20 elevation to a point at a higher elevation from which it may be supplied to the parts to be lubricated. It consists of the elements and features of construction shown and described, as indicated in the claims.

25 In the drawings:

Figure 1 is a vertical axial section of a device embodying this invention, the same being shown with suitable connections from the liquid supply and to the parts to be served and to the vacuum-producing device, neither the main liquid supply nor the part to be served nor the vacuum producing device being shown.

Fig. 2 is an axial section of the diaphragm-operated valve and its connections which constitute the distinguishing feature of the device upon a larger scale than the same is shown in Fig. 1.

Fig. 3 is a side elevation showing the liquid-elevating device connected to the manifold and carburetor of an internal combustion engine.

The structure shown in the drawings comprises a pumping device consisting of a partial vacuum chamber, A, and a fuel-receiving chamber, B, partitioned from each other by a flexible diaphragm C, which carries a valve D, for controlling inlet into the chamber A, by seating upon the valve seat, e, at the port of the inlet through the pipe, E, the diaphragm, C, being bound at its periphery between the disks, F and G, which form the outer walls of the two chambers, A and B, respectively, and being normally 55 adapted to bulge one way or the other out of the plane of its bound periphery—that is,

toward one or the other of the disks, F and G, and being elastic so that it tends to "buckle" and reverse its bulge suddenly upon having its center forced from bulged 60 position at one side, to the plane of its bound periphery. By reason of such elasticity and bulged form the diaphragm at that intermediate position,—that is, the position at which its center is substantially in 65 the plane of its bound periphery, is in what may be called "unstable equilibrium" between the opposing tendencies to bulge in the two opposite directions. The valve, D, is carried by the diaphragm, C, by being 70 mounted in a small bracket, H, secured substantially at the center of the diaphragm, having a bearing axial with respect to the diaphragm for the stem, d, of the valve, said stem extending through the bearing 75 and being provided with a check pin, d', below the bearing, and at such distance from the valve head with respect to the length of the bearing, that the valve has a little play longitudinally of its stem in said bearing. 80 This play is designed to be less than the range of buckling of the diaphragm from one of its bulged positions to the opposite bulged position, and for the best operation of the device, the range of free movement 85 of the valve should be slightly more than half of the buckling movement of the diaphragm—that is, should be a little more than the movement of the center of the diaphragm from its bulged position in either 90 direction to the point at which it will tend to buckle in the opposite direction. The pipe, E, is connected with the source of suction or means of producing partial vacuum. When the device is applied to the purpose of 95 elevating the liquid fuel of an internal combustion engine from a lower to a higher level, the pipe may be connected with the manifold of the engine for producing the desired suction; and in such case it is preferably provided with a check valve, E', opening in the direction in which the suction operates and tending to seat in the opposite direction, so that in the pulsation of 100 pressure arising in the manifold of the engine, only the exhaust or suction impulse will take effect in the device shown, so that beyond that check valve in the direction of the diaphragm chamber, there will always be a partial vacuum due to the intake stroke 110 of the engine piston, and at no time a pressure in the opposite direction resulting from the

opposite stroke. The chamber, B, at the opposite side of the diaphragm from the vacuum connection described has a liquid inlet connection provided through a pipe, 5 K, and a liquid outlet connection through a fitting, L, formed upon the outer side of the disk, G. In the liquid inlet connection there is provided a check valve M, opening to admit the liquid and seating by reverse 10 or outward flow; and in the liquid outlet fitting there is provided a check valve, N, which opens to permit the outflow of the liquid and is seated by reverse flow. Mounted upon the side of the disk, G, opposite 15 that at which the diaphragm is situated, there is a liquid receptacle P, into which the outlet connection, L, opens, and into which therefore liquid which may be admitted to the chamber, B, through the inlet 20 pipe, K, may be discharged through the outlet connection, L, past the check valve, N. As a matter of compactness of construction, the inlet pipe, K, extends through the bottom wall of the receptacle, P, in order to 25 reach its connection with the disk, G, for inlet into the chamber, B. The receptacle, P, has an outlet connection, Q, at the lower part by which the liquid entering said receptacle, P, past the check valve, N, may 30 flow by gravity, for instance to the carburetor, when the device is employed to supply liquid fuel to the engine. And to permit such free flow by gravity, the receptacle, P, has at the upper part, an atmospheric 35 inlet connection, R, which may be connected with a filling funnel, W. A coiled spring, T, centered about the intruding end of the pipe, E, in the chamber, A, reacts between the wall, F, of said chamber and the diaphragm, C, with a tendency to buckle the diaphragm toward the opposite wall, G; and said spring is stiff enough to reverse the buckle or bulge of the diaphragm in the direction indicated when the pressure in the 40 two chambers, A and B, is equal, but it is not stiff enough to prevent the diaphragm being bulged toward the chamber wall, F, by the lowest degree of suction operating through the pipe, E, at which the device is 45 designed to be operated. Through the wall, F, of the chamber, A, there is made a leak-port, U, for admission of atmospheric pressure. The capacity of this port is small 50 relatively to the suction port controlled by the valve, D.

When the pipe E, is connected with a source of suction or means of producing partial vacuum, and the liquid inlet pipe, K, is connected with a source of the liquid to be 55 elevated by the device, the partial vacuum operating through the pipe, E, upon the diaphragm, C, causes it to be buckled and bulged toward the chamber wall, F, and to seat the valve, D, upon the seat, e. The instant the valve is thus seated, however, and

the suction is cut off, atmospheric pressure admitted through the leak-port, U, equalizing the pressure in the two chambers, A and B, causes the spring, T, to reverse the bulge of the diaphragm, C, and in the latter 70 part of the reversing the movement, that is, in the movement after the diaphragm at the center has been pushed past the plane of its bound periphery, the valve, D, is pulled off its seat and the suction again admitted, 75 but not so promptly as to prevent the finishing of the buckling movement of the diaphragm by its own reaction, thus insuring the complete unseating of the valve, and admitting the suction with its full force, thus preventing the arising of a condition of equilibrium between the suction, and the atmospheric pressure through the leak-port, U. The suction being now operative as at first 80 in the chamber, A, buckles the diaphragm 85 in the opposite direction, seating the valve as before, whereupon the atmospheric pressure admitted through the leak-port, U, causes a repetition of the movement above described, re-opening the valve; and thus 90 from the continuous suction, there will result a rapid vibration of the diaphragm, alternately seating and unseating the valve, D. This alternate vibration of the diaphragm operates with a pumping action to 95 lift the liquid through the inlet pipe, K, and discharge it through the fitting, L, into the receptacle P, from which, by reason of the free atmospheric communication at the upper part of said receptacle, the liquid is free 100 to flow by gravity through the outlet, Q.

To prevent the receptacle, P, from being over-filled which might happen in case the drainage to the carburetor or for whatever service the device is employed is less than 105 the pumping capacity of the device, the liquid supply pipe, K, has an opening, k, controlled by a valve, X, opening into the receptacle, P, and connected with a float, Y, which opens said check valve when the receptacle is filled above a pre-determined 110 level at which the said float is positioned, said valve being held securely closed by its weight and the weight of the operating connections including the float, so long 115 as the liquid level does not rise to the float. When the valve, X, is opened by the operation of the float, the pumping action of the diaphragm merely passes the liquid around and around in a circuit from the receptacle, P, through the pipe, K, into the chamber, B, back again past the check valve, N, into the receptacle, P.

I claim:—

1. A device for the purpose indicated 125 comprising a partial vacuum chamber, a liquid chamber, and an elastic bulged diaphragm which partitions said chambers from each other; a conduit leading into the liquid chamber; a receptacle with which said 130

- liquid chamber communicates; a check valve controlling said communication arranged for flow of liquid into the receptacle and for seating by reverse flow, said receptacle having a vent to the atmosphere; a valve carried by the diaphragm in the partial vacuum chamber, said partial vacuum chamber having an outlet port and a seat for the valve at said port, the connection between the valve and the diaphragm providing a lost motion of a range less than the buckling movement of the diaphragm, the partial vacuum chamber having a leak-port for atmospheric inlet smaller than the outlet port, and yielding means tending to buckle the diaphragm in the direction for unseating the valve. 5
2. A device for the purpose indicated comprising two chambers, a member mounted for movement back and forth between said chambers for alternately increasing and diminishing the capacity of each and simultaneously diminishing and increasing the capacity of the other; a spring tending yieldingly to force and hold said member at one limit of its range of movement, said member being constructed and mounted for unstable equilibrium at an intermediate point in said range; a suction passage communicating with one of said chambers; a valve which controls said communication carried by said movable member and mounted thereon for free movement with respect to said movable member less than the range of movement of the latter; the other of said chambers having an inlet and a discharge connection, and check valves in said connections which respectively permit inflow and discharge and which are seated by reverse flow. 10
3. A device for the purpose indicated, comprising two chambers, a member mounted for movement back and forth between said chambers for alternately increasing and diminishing the capacity of each and simultaneously diminishing and increasing the capacity of the other; a spring tending yieldingly to force and hold said member at one limit of its range of movement, said member being constructed and mounted for unstable equilibrium at an intermediate point in said range; a suction passage communicating with one of said chambers; a valve which controls said communication carried by said movable member and mounted thereon for free movement with respect to said movable member less than the range of movement of the latter, the other of said chambers having an inlet and a discharge connection and check valves in said connections which respectively permit inflow and discharge and are seated by reverse flow; and a receptacle into which said discharge leads, having atmospheric communication at the upper part and a discharge connection at the lower part. 15
4. A device for the purpose indicated, comprising two chambers, a member mounted for movement back and forth between said chambers for alternately increasing and diminishing the capacity of each and simultaneously diminishing and increasing the capacity of the other; a spring tending yieldingly to force and hold said member at one limit of its range of movement, said member being constructed and mounted for unstable equilibrium at an intermediate point in said range; a suction passage communicating with one of said chambers; a valve which controls said communication carried by said movable member and mounted thereon for free movement with respect to said movable member less than the range of movement of the latter, the other of said chambers having an inlet and a discharge connection, and check valves in said connections which respectively permit inflow and discharge and are seated by reverse flow; a receptacle into which said discharge leads, having atmospheric communication at the upper part and a discharge connection at the lower part; the inlet pipe extending through said receptacle and having an opening thereinto; a valve in the receptacle closing said opening and a float connected with the valve for opening it when the liquid in said receptacle reaches a pre-determined level. 20
5. A device for the purpose indicated comprising two chambers, a member mounted for back-and-forth movement between said chambers for alternately increasing and diminishing the capacity of each and simultaneously diminishing and increasing the capacity of the other; means tending yieldingly to force and hold said member at one limit of its range of movement, said member being constructed and mounted for unstable equilibrium at an intermediate point in said range; a suction passage communicating with one of said chambers; a valve which controls said communication carried by said movable member and adapted to permit a limited movement of the diaphragm less than its full range of movement before closing and also before opening the valve, the other of said chambers having an inlet and a discharge connection, and suitable means controlling them respectively. 25
6. In combination, an internal combustion engine, an intake supply pipe therefor, a carburetor connected to said intake supply pipe, a fuel supply tank, and a pneumatically operated pumping device having a pumping chamber of variable size and a separate motor chamber of variable size, the variations in size of the pumping chamber being dependent upon the variations in size of the motor chamber, the motor chamber of said pumping device being connected to the atmosphere and to said intake supply pipe so as to be varied in size by the vacuum 30

of such intake supply pipe, and the pumping chamber of said pumping device being connected to said fuel supply tank and said carbureter so as to force fuel from the fuel tank to the carbureter when varied in size by the action of said vacuum on said motor chamber.

7. A vacuum feed device comprising a chamber having a movable wall, and having 10 an outlet for connection to a partial vacuum, said chamber having an inlet leading from the atmosphere to said chamber, and a valve which controls said outlet, and connection from said movable wall to said valve for 15 closing it by the movement of said wall to ensmall the chamber, and opening it upon movement of said wall to enlarge the chamber.

8. A vacuum power device comprising a 20 hollow casing, a flexible diaphragm closing said casing to provide a closed chamber therein, said chamber having an outlet for connection to a partial vacuum, and an inlet connecting said chamber with the atmosphere, a valve controlling said outlet, a spring tending to move said diaphragm in the direction to enlarge said chamber, and connections between said diaphragm and said valve for closing it upon the flexing of 25 the diaphragm inward, and for opening it upon the flexing of the diaphragm outward relatively to such chamber.

9. A vacuum power device comprising a 30 hollow casing, a flexible diaphragm closing said casing to provide a closed chamber therein, said chamber having an outlet for connection to a partial vacuum, and an inlet for connection with the atmosphere, a valve controlling said outlet, and connections between said diaphragm and said valve for closing the valve upon the flexing of the diaphragm inward, and opening it upon the flexing of the diaphragm outward relatively to such member.

45 10. A vacuum power device comprising a hollow casing, a flexible diaphragm closing said casing to provide a closed chamber therein, said chamber having an outlet for connection to a partial vacuum, and an inlet for connection with the atmosphere, and a valve controlling said outlet, a spring tending to move said diaphragm in the direction to enlarge said chamber, connections between said diaphragm and said valve for 50 closing the valve upon the flexing of the diaphragm inward, and opening it upon the flexing of the diaphragm outward relatively to such chamber; a cover for said diaphragm, said cover and diaphragm together 55 forming a separate chamber partitioned from the first, and automatic valves opening

into and away from said second chamber respectively.

11. A vacuum power device comprising a hollow casing, a flexible diaphragm closing 65 said casing to provide a closed chamber therein, said chamber having an outlet for connection to a partial vacuum and an inlet for connection with the atmosphere, and a valve controlling said outlet, connections between said diaphragm and said valve for closing the valve upon the flexing of the diaphragm inward, and opening it upon the flexing of the diaphragm outward relatively to such chamber, a cover for said diaphragm, 70 said cover and diaphragm together forming a separate chamber partitioned from the first, and a pair of automatic valves opening into and away from said second chamber respectively.

12. In combination, an internal combustion engine, an intake manifold therefor, a carbureter connected to said intake manifold, a closed casing, an intermediate diaphragm in said casing dividing it into two 85 separate chambers, one of said chambers having an outlet and connections from such outlet to the intake manifold, and having an inlet for communication with the atmosphere, a valve which controls said outlet, 90 connections from said diaphragm to said valve so that as the diaphragm flexes to ensmall said first chamber, it closes said valve, and as it flexes to enlarge said chamber it opens said valve, a fuel supply tank, a connection from said fuel supply tank to the second chamber, a valve in said connection opening toward said second chamber, a connection from said second chamber to said carbureter, and a valve in said last named 100 connection opening from said second chamber toward the carbureter.

13. In combination, an internal combustion engine, an intake supply pipe therefor, a carbureter connected to said intake supply 105 pipe, a fuel supply tank, and a pneumatically-operated pumping device provided with a flexible partition forming a motor side and a pump side, and having its motor side connected to the atmosphere and to 110 said intake supply pipe so as to be actuated by the vacuum of said intake supply pipe, and having the intake and exhaust of its pump side connected to said fuel supply tank and said carbureter respectively.

In testimony whereof I have hereunto set my hand at Detroit, Michigan, this 23rd day of October, 1914.

WEBB JAY.
